W. T. Myers Inventor

By *Chas. W. C. Brown* Attorney

UNITED STATES PATENT OFFICE.

WILLIAM L. MYERS, OF INDUSTRY, ILLINOIS.

LATCH.

Application filed April 3, 1922. Serial No. 549,214.

To all whom it may concern:

Be it known that I, WILLIAM L. MYERS, a citizen of the United States, residing at Industry, in the county of McDonough and State of Illinois, have invented a new and useful Latch, of which the following is a specification.

This invention relates to latches, and more particularly to latches especially designed for use for securing swinging closures operating in horizontal planes.

Another object of the invention is to provide a latch adapted to fall by gravity, to its active or latching position.

15 A still further object of the invention is to provide a guard forming a part of the latch, whereby the latch may be used for securing barn doors or the like, the guard preventing an animal from operating the same to unlatch the closure.

20 With the foregoing and other objects in view which will appear as the description proceeds, the invention resides in the combination and arrangement of parts and in 25 the details of construction hereinafter described and claimed, it being understood that changes in the precise embodiment of the invention herein disclosed, may be made within the scope of what is claimed, without departing from the spirit of the invention.

Referring to the drawing:

Figure 1 is an elevational view of a latch constructed in accordance with the present 35 invention.

Figure 2 is an elevational view of the latch, the guard being partly broken away to illustrate the latch arm.

Figure 3 is a plan view of the latch.

40 Figure 4 is a sectional view taken on line 4-4 of Figure 1.

Figure 5 is a sectional view taken on line 5-5 of Figure 1.

Referring to the drawing in detail, the 45 latch embodies a plate 5 having a right angled tongue 6 formed integral therewith, the plate also being provided with openings to accommodate a suitable securing means, whereby the plate may be secured to the 50 door jamb. Pivottally supported on the plate 5, is a latching arm 7 which is formed with a right angled extremity 8 adapted to cooperate with the ears 6 of the plate 5 to secure the latching arm 7 in a locking position.

The right angled end of the arm 7, which

is indicated at 9, is formed with an opening 10 to receive the shackle of a padlock as clearly shown by Figure 1 of the drawing, so that the arm may be locked against 60 movement.

As shown, the arm 7 has pivotal connection with the plate 5 at a point adjacent to one end of the arm, the remaining portion of the arm being designed to move over 65 a point of contact between the movable closure or door operating against the jamb on which the plate 5 is supported. Thus it will be seen that when the arm 7 is moved to a position as shown by Figure 1 of the drawing, the closure will contact with the arm 7 to restrict movement of the closure.

When the arm 7 is moved to a position as illustrated in dotted lines in Figure 2 of the drawing, it is obvious that the arm is 70 out of the path of travel of the closure to the end that the closure may be moved to its open position. It might be further stated that the tongue 6 acts as a support for the arm 7, when the arm 7 has been moved 75 to its unlocked position.

Associated with the latch member is a keeper including a guard plate 11, which is formed preferably of sheet metal and provided with leg portions 12, each of which 80 being formed with a right angled extremity 13 to provide means for securing the guard to the closure or door. This guard is of a construction to extend over the point of contact between the door and its jamb to 85 substantially house the arm 7, and prevent movement thereof by the nose of an animal endeavoring to operate the latch member.

The arm 7 when in its locking position, contacts with one of the leg portions 12 90 of the guard, whereupon the arm is held in its locking position.

If it is desired to move the arm to its unlocked position, a person may by gripping the outer or free end of the arm move the 100 same on its pivot to a position as shown in dotted lines in Figure 2 of the drawing.

Having thus described the invention, what is claimed as new is:—

In a latch, a base plate having a right 105 angled tongue formed intermediate its ends and disposed adjacent to one of the side edges thereof, a pivoted arm having connection with the base plate and having a right angled extremity cooperating with the tongue to lock the closure supporting the latch, said tongue and right angled end 110

having openings to accommodate a locking element, a keeper including a plate having leg portions formed integral therewith, said plate adapted to overlie a portion of the base 5 plate and the tongue, said pivoted arm adapted to move to a position to engage one of the leg members of the keeper, and the last mentioned plate providing a guard.

In testimony that I claim the foregoing as my own, I have hereto affixed my signature in the presence of two witnesses. 10

WILLIAM L. MYERS.
